BALL-POINT PENCIL

Robert J. Harper, Scarsdale, and Robert H. Ensign,
Bronxville, N. Y., assignors to Scripto, Inc., a corpora-
tion of Georgia

Application August 6, 1956, Serial No. 42,529

Term of patent 14 years

(Cl. D74—24)

Fig. 1

Fig. 2

Fig. 3

Fig. 4

Fig. 1 is a front elevational view of a ball point pencil showing our new design;

Fig. 2 is a side elevational view of the ball point pencil shown in Fig. 1 as it appears with the writing point in retracted position;

Fig. 3 is a top plan view thereof; and

Fig. 4 is a bottom view thereof.

This application is a continuation-in-part of our application Serial No. D. 38,370, filed on October 14, 1955, and now abandoned.

We claim:

The ornamental design for a ball point pencil, as shown and described.
